UNITED STATES PATENT OFFICE.

HERVE A. LONSWAY, OF BERWICK, OHIO.

SHEARS FOR CUTTING JAR RINGS AND SIMILAR CIRCULAR WASHERS.

Application filed July 25, 1927. Serial No. 208,384.

This invention relates to shears adapted particularly for the cutting of rubber jar rings and similar circular washers and has for an object to arrange the blades of the shears whereby the jar ring or washer may be easily and quickly cut by a single operation in unbroken form from a flat sheet of material.

A further object is to provide an article of this character of simple and practical construction, efficient in operation, inexpensive to manufacture, and otherwise well adapted for the purposes for which the same is intended.

Other objects and advantages reside in the special construction and combination of the various elements of this invention, reference being had to the accompanying drawings forming a part hereof, wherein:

Figure 1 is a top plan view of a pair of shears constructed in accordance with my invention.

Figure 2 is a side elevational view thereof,

Figure 3 is a vertical sectional view taken along a line 3—3 of Figure 2,

Figure 4 is a plan view of a fragment of material in sheet form, and folded upon itself in position for cutting a circular washer therefrom, and,

Figure 5 is a plan view of the washer after being cut from such material.

Referring now to the drawing wherein for the purpose of illustration I have disclosed a preferred embodiment of my invention, I provide a pair of shears including handle sections 5 secured at one end by a spring member 6 of a type adapted to normally maintain the handles in a spread position and having blades 7 formed at the opposite ends thereof.

Each of the handles 5 are provided with a pair of blades arranged in opposed relation and as indicated by Figure 2 of the drawing with the cutting edges 8 thereof arranged in alined position for simultaneous cutting action.

The ends of the blades are curved upwardly in semi-circular formation, with the blades of each handle made in an evenly spaced parallel position with respect to each other. Thus the upper blades 7 which are uppermost at the connection thereof with the handles are disposed under the lower blades 9 at the termination of the ends thereof.

With the blades arranged in the manner as described above, the same are adapted to cut a continuously formed circular washer as indicated at 10 from a sheet of material 11 such as shown in Figure 4, it first being necessary to fold the material upon itself and to cut the washer from the folded edge as shown by the dotted lines indicated at 12.

The device is admirably adapted for cutting rubber jar rings and the like from sheet rubber material and it has been found that old inner tubes are especially adapted for providing the material from which such rings or washers may be cut. It is to be understood, however, that the tool may be used for cutting washers or rings from any material such as paper, cardboard, sheet cork or the like, and also from relatively soft metal.

It is obvious that the invention is susceptible to various changes in the shape, size and form thereof, without departing from the spirit or scope of the appended claim, and I accordingly claim all such forms of the device to which I am entitled.

I claim:

In a tool of the class described, a plurality of cutting blades arranged in pairs in opposed relation, the outer end of each pair of blades being curved in a semi-circular formation and retained in spaced parallel relation with each other, said blades co-acting with each other whereby to cut a circular washer from a sheet of material when arranged in folded position at one cutting operation.

In testimony whereof I affix my signature.
HERVE A. LONSWAY.
